CLASSROOM MUSIC STAND

Mack Perry, 2917 Ave. R, Brooklyn, N.Y.

Filed Mar. 8, 1960, Ser. No. 59,662

Term of patent 14 years

(Cl. D33—10)

FIG. 1 is a front perspective of classroom music stand showing my new design.

FIG. 2 is an end view of classroom music stand.

FIG. 3 is a rear elevational view upon a reduced scale as compared to FIGS. 1 and 2.

FIG. 4 is a bottom elevational view upon a reduced scale as compared to FIGS. 1 and 2.

The end of the music stand not shown is the same in appearance as the end shown.

I claim:

The ornamental design for classroom music stand, as shown and described.
